UNITED STATES PATENT OFFICE.

HERMAN L. MONTGOMERY, OF METZ, WEST VIRGINIA.

GRIP.

SPECIFICATION forming part of Letters Patent No. 674,246, dated May 14, 1901.

Application filed February 21, 1901. Serial No. 48,310. (No model.)

To all whom it may concern:

Be it known that I, HERMAN L. MONTGOMERY, a citizen of the United States, residing at Metz, in the county of Marion, State of West Virginia, have invented certain new and useful Improvements in Grips; and I do hereby declare the following to be a full, clear, and exact description of the invention, such as will enable others skilled in the art to which it appertains to make and use the same.

This invention relates to oil-well pumps; and it has for its object to provide a grip for holding the pump-rod against slipping during the adjustment of the rod with respect to the walking-beam, the object of the invention being to provide a simple, cheap, and efficient construction which may be easily operated for the purpose designed.

In the drawings forming a portion of this specification, and in which like numerals of reference indicate similar parts in the several views, Figure 1 is an elevation showing an oil-pump in operative position and provided with the present device. Fig. 2 is a longitudinal section through the grip removed from the pump. Fig. 3 is a transverse section through the grip with the pump-rod in place.

Referring now to the drawings, 5 represents the barrel of an oil-pump having a head 6 and discharge-pipe 7. In the pump-barrel is the usual pump-rod 8, which extends upwardly through the head thereof and which at its upper end is engaged with the grip 9 at the end of the walking-beam 10.

The upper end of the pump-head is internally threaded, as usual, to receive a stuffing-box, and in the place of this usual stuffing-box is placed the present grip.

The grip consists of a cylindrical body 11, having reduced end portions 12 and 13, which are exteriorly threaded, the end portions of the enlarged central part of the body being preferably beveled, as shown. Formed centrally through the body is an annular passage 14, of a size to snugly receive the pump-rod, and in the inner wall of the body and extending longitudinally thereof from the end 13 to a point adjacent to the end 12 is a cross-sectionally rectangular passage or groove 15, in which is slidably disposed a gripping-block

16, this block having its bottom channeled, as shown at 17, to present two gripping-faces 18 and 19, which when the block is moved toward the center of the opening through the grip-body frictionally engage the pump-rod 55 and hold it against movement through the opening of the body.

To move the gripping-block into and out of gripping position, said block has a T-shaped groove cut longitudinally thereof in its face 60 opposite to the gripping-faces and extending from one end of the block to a point adjacent to the other end of the block, and in this groove are engaged the heads 20 and 21 of two machine-screws 23 and 24, which are engaged with 65 threaded perforations 25 and 26, which are formed through the body of the grip and communicating with the groove 15. The heads 20 and 21 are annular and are connected with the bodies of the screws by reduced necks, as 70 shown, lying in the reduced portion of the groove of the gripping-block. The turning heads of the screws of course lie exterior of the body 11 for engagement of a wrench to rotate the screws, and when said screws are rotated in 75 one direction they work inwardly to move the gripping-block inwardly, and when the screws are reversely rotated they move the block into releasing position.

In assembling the parts of the grip the 80 screws are first engaged with the body 11 and the block is then slid into the groove 15 to receive the annular heads of the screws in its groove.

This grip is screwed with its end 12 into 85 the pump-head in the place of the stuffing-box, and upon the opposite end of the body is screwed a collar 27, in which is a recessed bushing 28, which closely fits the pump-rod. Packing material is placed in the collar upon 90 the bushing, after which a second bushing 28' is screwed into the collar to compress the packing in the usual manner. With this construction it will be seen that if at any time it is desirable to shift the position of the pump-rod the grip on the pump-head may be operated to grip the rod and hold it against movement, after which the grip that holds the rod to the walking-beam may be released and the beam adjusted to the proper degree, after 95 100

which the walking-beam grip may be engaged with the rod and the pump-head grip afterward released.

What is claimed is—

- 5 A grip comprising a sleeve having a longitudinal interior groove in one face and having threaded perforation communicating with said groove, a block slidably engaged with the groove for movement toward and away from
- 10 the center of the sleeve, said block having a T-shaped longitudinal groove therein, and screws engaged with the threaded perfora-

tions of the sleeve and having heads slidably engaged with the groove of the block for adjusting the block, said block having a longitudinally-grooved inner gripping-face.

In testimony whereof I hereunto sign my name, in the presence of two subscribing witnesses, on the 23d day of January, 1901.

HERMAN L. MONTGOMERY.
